UNITED STATES PATENT OFFICE.

RICHARD A. WALKER, OF SKIDMORE, MISSOURI.

BURNER.

Application filed September 14, 1923. Serial No. 682,761.

To all whom it may concern:

Be it known that I, RICHARD A. WALKER, a citizen of the United States, residing at Skidmore, in the county of Nodaway and State of Missouri, have invented new and useful Improvements in Burners, of which the following is a specification.

This invention relates to oil burners of the type adapted for burning fuel oil or distillate.

In all burners of this general character, considerable difficulty is encountered in the proper operation or use of the burner, resulting from poor, medium or strong drafts furnished by many different sizes and styles of flues, and a great percentage of such troubles rises from the formation of soot or carbon, which is the cause of both fire and filth. Then again, the improper mixture resulting from poor combustion, furnishes an insufficient and unsatisfactory heat, notwithstanding the consumption of an excessive amount of fuel. Furthermore, it is not infrequent to have the flame extinguished in such burners by an excessive draft, which sometimes causes explosions with the resultant damage.

It is therefore the purpose of this invention to provide means of novel construction to overcome the above enumerated objects, by making it possible to obtain a proper mixture and a consequent proper combustion and operation of the burners with any kind of draft, that is to say whether the draft is good, poor or medium, the invention particularly eliminating the troublesome formation of carbon.

Another object of the invention resides in the provision of means whereby access may be readily had to the interior of the burner, or any part which requires cleaning from time to time, or for any purpose whatsoever.

The nature and advantages of the invention will be better understood when the following detailed description is read in connection with the accompanying drawings, the invention residing in the construction, combination and arrangement of parts as claimed.

In the drawings forming part of this application, like numerals of reference indicate similar parts in the several views, and wherein:

Figure 1 is a top plan view of the burner constructed in accordance with the present invention.

Figure 2 is a side elevation partly in section showing the component parts separated.

Figure 3 is a sectional view taken on the line 3—3 of Figure 1 showing the arrangement of parts when only a poor draft is obtainable.

Figure 4 is a view similar to Figure 3 showing the arrangement of parts when there is a strong draft.

Figure 5 is a detail view of one of the adjusting rings.

Referring to the drawings in detail, 10 indicates the base of the burner which is substantially dish shaped or curvilinear as shown, although the central portion of the base is elevated as at 11 and formed with a series of concentrically disposed grooves or troughs 12. Then again, the center of this base is provided with a fuel inlet opening 13 in which one end of a supply pipe is threaded. The bottom adjacent one edge is provided with an overflow opening 15 into which is threaded an overflow pipe 16. Projecting from this bottom but forming an integral part thereof, are air inlet passages 17, the latter being arranged at diametrically opposed points above the base as clearly illustrated in Figure 1. It will be noted that the air inlet passages 17 are on the outside of the bowl portion of the base, thus preventing the air which passes upwardly through the opening 17 from cooling the bowl as quickly as where the air openings are located inside the bowl portion of the base. This is a very important feature in burners of this character, as it allows the fire to be turned down very low, which cannot be done with burners in present day use where the air inlet openings are arranged on the inside, due to the cooling effect of the air on the bowl portion of the burner. The shape of these openings can vary without departing from the spirit of the invention and this is also true in regard to the size of such passages. The wall of each passage is cut away at the upper end thereof to provide a recess 18, the purpose of which is to be presently described.

The top of the burner is as shown, formed with a depending centrally arranged portion 19, which is preferably of cylindrical formation in cross section, and adapted to be arranged immediately above the elevated central portion 11 of the base 10 to direct the draft or air downwardly.

on the base as will be readily understood. Radiating from this central portion 19 is a plurality of flues or conduits 20, the latter being curved outwardly and downwardly 5 from the central portion and terminating in a plane an appreciable distance below the plane occupied by the lower edge of the centrally disposed portion 19. There is one flue or conduit 20 for each air passage 17, 10 the latter receiving the lower ends of said conduits, in a manner whereby the top member is supported upon the base. In other words, each conduit or flue is provided with an annular flange or shoulder 21 15 which reposes upon the bottom of the recess 18 above referred to.

The top member is provided with a central opening arranged immediately above the portion 19, and this opening is normally 20 closed by a cap 22 formed with a flange 23 which reposes upon an inwardly directed flange 24 forming an integral part of the top member. The flange 23 of the cap is provided with draft openings 25 as is also the 25 flange 24 of the top member, the openings in the latter being indicated at 26. The cap is not only removably associated with the top member but it is susceptible of being rotated for the purpose of allowing the 30 openings thereof to be moved into or out of registration with the openings of the flange 24, with a view of allowing a portion of the excessive air to pass outwardly through these openings instead of forcing all air 35 downwardly against the bottom or bowl of the burner. The cap is provided with an opening 27 to facilitate handling of the cap or for the purpose of removing it from the top member or for turning it for the purpose just stated. The invention embodies a 40 plurality of adjusting rings 29 of a shape to correspond to the configuration of both the recess 18 and the cross sectional configuration of each conduit or flue 20. These 45 rings being used to adjust the top member with relation to the base or bowl of the burner, so that a proper mixture and combustion for a proper operation of the burner may be obtained with either a poor, or medium draft. It is of course to be understood that a number of these rings will be 50 provided for each burner, the rings varying in dimensions so that a proper adjustment of the top member with relation to the base or bowl of the burner can be obtained to 55 meet any requirement. Upon inspection of Figure 3, it will be noted that the top member is supported by the base without the use of any of the rings just referred to, and 60 in this position of the parts it will be observed that the tubular portion 19 of the top terminates at a point in close proximity to the central elevated portion of the bowl or base 10, insuring a proper mixture of the 65 air and vaporized oil with a poor draft, a

thing that positively is impossible with a strong draft. However, in case of a strong draft, this tubular portion 19 of the top can be elevated and spaced the required distance away from the central elevated portion 11 of the base by using a set of rings of the proper dimensions, depending of course upon the draft condition, and when these rings are used they are positioned in the manner shown in Figure 4. When the 70 use of these rings are resorted to, there is one ring associated with each fluid or conduit 20, the rings being interposed between the flanges of each flue, and the bottom of the recess 18 formed on the base member. Consequently, the tubular portion 19 is spaced the required distance away from the bowl or base to insure the proper mixture of air and vaporized oil. The adjustment 75 of the top member with relation to the base in this manner makes it possible to obtain a proper combustible mixture with any sort of draft condition, thus obtaining a most satisfactory flame and heat with the consumption of a minimum amount of fuel, but 80 more particularly, overcoming the objectionable features herein above enumerated, and particularly the objectionable formation 85 of carbon.

The burner is used in the usual well known manner, the base 10 being designed to provide what may be termed a bowl in which a priming charge is initially arranged, this charge being conveyed to the bowl through the fuel supply pipe. This 90 charge is then ignited, and permitted to burn for the purpose of properly heating the bowl after which the oil is allowed to enter the bowl through the supply pipe. The vapor is then ignited and mixed with 95 the air which passes upwardly into the air passages through the flue or conduit 20 which conveys the air into the centrally arranged tubular portion 19 passing downwardly through this portion into the base as in 100 other burners. Any overflow of oil will be taken care of by the overflow pipe above mentioned, while any excessive air or draft can be regulated by means of the damper 105 which the cap of the top member actually 110 provides.

While it is believed that from the foregoing description, the nature and advantages of the invention will be readily apparent, I desire to have it understood that I do not limited myself to what is herein shown and described and that such changes may be resorted to when desired as fall within the scope of what is claimed.

Having thus described the invention, I 125 claim:

1. In an oil burner, a base designed to 130 form a fuel receiving bowl, a fuel supply pipe communicating therewith, an overflow pipe leading from said bowl, said base be-

ing further formed to provide a plurality of air inlet openings, a top member supported upon the base and including a centrally disposed tubular portion, flues radiating 8 from said portion and terminating beneath the bottom thereof, and adapted to be received by the air inlet openings, said top member having a central opening arranged immediately above the tubular portion, a 10 flange projecting inwardly from the wall of said opening and having a circular series of slots, a cap closing said opening and supported by said flange, said cap having slots adapted to be moved into and out of registration with the slots of said flange to regulate excessive draft, and means for adjusting the top member with relation to the bowl to position the tubular member at different distances above the latter for the purpose specified.

2. In an oil burner, a base designed to provide a fuel receiving bowl having its central portion elevated within the bowl and formed to provide a series of concentrically 25 arranged grooves, a fuel supply pipe communicating with the bowl centrally thereof, said base being further formed to provide a plurality of air inlet passages, a top member supported by the base and including a centrally arranged tubular portion disposed immediately over the centrally elevated portion of the bowl, conduits radiating from said tubular portion and projecting beneath the latter, and adapted to be received by the 30 air inlet openings, a damper carried by the top member immediately above the tubular

portion, and means whereby the top portion may be adjusted with relation to the bowl to space the tubular portion of the top member at different distances away from the centrally elevated portion of the latter for the purpose specified. 40

3. In a fuel burner, a base designed to provide a fuel receiving bowl, the central portion of which is elevated within the 45 bowl, and formed to provide a series of concentrically arranged grooves, a fuel supply pipe communicating with the bowl centrally thereof, said base being further formed to provide diametrically opposed air inlet passages, a top member including a centrally arranged tubular portion disposed immediately above the elevated portion of said bowl, a conduit radiating from said tubular portion and terminating in a plane beneath 50 the lower edge thereof and adapted to be received by said air inlet passages, shoulders formed on said flues for supporting the top member upon the base, a damper on the top member and arranged immediately 55 above the tubular portion thereof, and ring like members adapted to be interposed between the shoulders of said flues and said base to vary the distance between these parts whereby the tubular portion of the top 60 member can be arranged in different positions with relation to the centrally elevated portion of the bowl for the purpose specified. 65

In testimony whereof I affix my signature.

RICHARD A. WALKER.
